CLAIM

The ornamental design for a waste oil receptacle, as shown and described.

DESCRIPTION

FIG. 1 is a front elevation view of a waste oil receptacle showing my new design;

FIG. 2 is a right side elevation view;

FIG. 3 is a left side elevation view;

FIG. 4 is a top plan view;

FIG. 5 is a bottom plan view; and,

FIG. 6 is a right side isometric view of a waste oil receptacle showing my new design.

1 Claim, 6 Drawing Sheets
